SLIPPER OR SIMILAR ARTICLE

David James Silver, New York, N. Y.

Application October 24, 1949, Serial No. 5,671

Term of patent 3½ years

(Cl. D7—7)

To all whom it may concern:

Be it known that I, David James Silver, a citizen of the United States of America, residing in New York, county of New York, and State of New York, have invented a new, original, and ornamental Design for a Slipper or Similar Article, of which the following is a specification, reference being had to the accompanying drawing, forming part thereof.

Fig. 1 is a perspective view of a slipper or similar article showing my new design.

Fig. 2 is a plan view of the sole portion of the slipper.

The opposite side of Fig. 1 is substantially the same as shown in the drawing.

I claim:

The ornamental design for a slipper or similar article, substantially as shown and described.

DAVID JAMES SILVER.
